United States Patent Office

Des. 213,796
Patented Apr. 8, 1969

213,796

PITCHER

Edward Marue, 11135 Blix St., North Hollywood,
Calif. 91602

Filed Sept. 9, 1968, Ser. No. 13,464

Term of patent 14 years

Int. Cl. D7—01

U.S. Cl. D44—21

FIG. 1 is a perspective view of a pitcher showing my new design;

FIG. 2 is a top plan view;

FIG. 3 is an elevational view from the left of FIG. 1;
and

FIG. 4 is an elevational view from the right of FIG. 1.
I claim:

The ornamental design for a pitcher, substantially as shown.
